FAGGOTING ATTACHMENT FOR SEWING MACHINES

Herbert H. Russell, New Haven, Conn., assignor to The Greist Manufacturing Company, New Haven, Conn., a corporation of Connecticut

Application April 27, 1951, Serial No. 223,399

7 Claims. (Cl. 112—179)

1

This invention relates to a sewing machine attachment and more particularly to an attachment for effecting a faggotting stitch. In work of this kind the finished edges of two pieces of material are loosely stitched together so as to leave a space between them, and the present invention is directed toward a sewing machine attachment which will effect stitching of this character.

In a device of this kind, the two pieces of material which are stitched together are held in spaced relation during the stitching operation so that the threads will be passed through both pieces of material while so spaced, the two pieces being sewed very loosely together so that when folded along or substantially along the line of stitches, they will be sewed together in spaced relation with the stitches extending from one piece of material to the other.

It is, of course, desirable to provide means for adjusting the spacing of the two pieces of material so that this spacing will be wide or narrow as desired, and the present invention relates particularly to means for adjusting this spacing in a convenient and satisfactory manner.

As illustrated, the device comprises a foot member secured to the presser bar of the sewing machine and a second arm or bar substantially parallel to the cloth-holding foot but spaced above the same. Both pieces of the cloth which are to be sewed together are passed under the foot, and one of them is passed over the arm so that the two pieces of cloth will be held in spaced relation when stitched together, the spacing of the arm from the level of the foot determining the width of the faggotting in the finished article.

In the present structure, convenient means are provided for adjusting the vertical spacing of the arm above the foot, and thus the width of the faggotting in the finished work.

One object of the present invention is to provide a new and improved sewing machine attachment for effecting faggotting operations, the attachment being adapted to be attached to the usual household sewing machine.

A further object of the invention is the provision of a new and improved faggotting attachment having improved means for adjusting the spacing arm relatively to the cloth-holding foot of the device so as to adjust the width of the faggotting stitch.

A still further object of the invention is the provision of a new and improved sewing machine attachment for effecting faggotting operations having a cloth-holding foot and an arm spaced in a plane vertically above the foot, the arm being adjustable to various positions with relation to the foot by a new and improved mechanism.

2

A still further object of the invention is the provision of a sewing machine attachment of the kind described which will be simple in construction, economical to manufacture, and readily adjustable so as to effect faggotting operations of various widths.

To these and other ends the invention consists in the novel features and combinations of parts to be hereinafter described and claimed.

10 In the accompanying drawing:

Fig. 1 is a front elevational view of a faggotting attachment embodying my improvements;

Fig. 2 is a top plan view thereof;

15 Fig. 3 is a view similar to Fig. 1, certain parts being shown in section and the parts being shown in another position; and

Fig. 4 is a side elevational view of the attachment showing the use thereof.

To illustrate a preferred embodiment of my 20 invention I have shown in the drawing a faggotting attachment comprising a cloth-holding foot 10 which is provided with an adapter 11, the adapter being arranged for attachment to the presser bar of the usual household sewing machine.

25 The rear end of the foot member 10 is enlarged as shown at 10^a and projecting upwardly therefrom is a pair of pins 12 and 13, the latter being threaded to receive a pair of knurled adjusting nuts 14 and 15.

30 The arm 16 is mounted upon the pins 12 and 13 and has an enlarged rear end portion 16^a which overlies the portion 10^a of the foot member and is provided with openings 17 and 18 which receive relatively snugly the pins 12 and 13 respectively so that the arm will be slidably mounted upon these pins for vertical adjustment 35 relatively to the foot member 10. It will be understood that when attached to the machine the foot member 10 and arm 16 extend substantially horizontally, and their longitudinal dimension is at right angles to the direction in which the cloth is moved through the machine.

40 The arm 16 is provided with a needle opening 20 and, as shown in Fig. 2, is slightly offset laterally from the foot 10 so that it does not lie directly above the foot 10 and, therefore, the needle passing through the opening 20 will not strike the foot.

45 Adjacent its rear end the arm 16 is upwardly offset, as shown at 21, so that the rear end 16^a of this arm is at a slightly higher level than the forward end 16, this rear end lying between the knurled adjusting nuts 14 and 15.

50 It will be understood that while the openings 17 and 18 of the arm 16 provide for slidable adjustment of this arm upon the pins 12 and 13 relatively to the foot 10 so that the arm may be

positioned at a greater or lesser distance above the foot, the offset 21 in the arm 16 provides for a closer adjustment of this arm to the level of the foot 10 than would be otherwise possible due to the fact that the lower nut 14 lies between the rear portion 16a of the arm and the foot member 10.

The operation of my device is shown in Fig. 4 where as illustrated one piece of the material 23 is shown passing under the foot 10 and lying substantially flatly on the bed of the machine. The other piece of material 24 also passes under the foot 10 but is displaced upwardly over the arm 16 so as to lie in spaced relation to the ply 23 when stitched by the needle 25, which passes through the opening 20 of the arm 16. It will be seen, therefore, that the two pieces of plies of material 23 and 24 will be stitched together loosely or in spaced relation so that they may be folded along the lines of stitching so that a space remains between them, this spacing being traversed by the stitches effected by the needle 25.

It will be obvious that the distance of the arm 16 above the foot 10 will determine the spacing of the two pieces of material when the operation is finished, and means, therefore, are provided for adjusting the vertical spacing of the arm 16 from the foot 10. This is effected by means of the knurled nuts 14 and 15 which are threaded upon the pin 13. The arm 16 is shown in a relatively high position in Fig. 1 so that there will be a relatively wide spacing between the two pieces of material. If it is desired to make this spacing narrower, the lower nut 14 is turned in the proper direction to lower it upon the pin 13, the arm 16 following the nut downwardly by sliding upon the pins 12 and 13. The upper nut 15 is then adjusted downwardly to clamp the rear portion 16a of the arm 16 tightly between the nuts 14 and 15, as shown for example in Fig. 3 where the arm 16 has been adjusted to a lower position.

It will be understood that the arm 16 is held against lateral movement with respect to the foot 10 and by means of its engagement with the pins 12 and 13, it being permitted only a vertical movement with respect to the foot to adjust the vertical spacing therebetween.

While I have shown and described a preferred embodiment of my invention, it will be understood that it is not to be limited to all of the details shown, but is capable of modification and variation within the spirit of the invention and within the scope of the claims.

What I claim is:

1. A sewing machine attachment for faggoting work comprising a foot member, means securing said member to the presser bar of a sewing machine, a cloth-supporting arm supported by the foot member substantially parallel thereto and in spaced relation thereto both laterally and vertically, and means for adjusting the arm vertically with respect to the foot.

2. A sewing machine attachment for faggoting work comprising a foot member, an arm member, the rear end of the latter overlying a portion of the former, the body portions of said members being disposed in substantially parallel vertically spaced relation, a threaded pin extending upwardly from the upper surface of the underlying portion of the foot member, said pin being received in an opening in the arm member, and adjusting nuts threaded on said pin and disposed one below and one above the arm member.

3. A sewing machine attachment for faggoting work comprising a foot member, an arm member,

the rear end of the latter overlying a portion of the former, the body portions of said members being disposed in substantially parallel vertically spaced relation, a threaded pin extending upwardly from the upper surface of the underlying portion of the foot member, said pin being received in an opening in the arm member, adjusting nuts threaded on said pin and disposed one below and one above the arm member, and a guide pin secured to one of said members and slidably received in an opening in the other member.

4. A sewing machine attachment for faggoting work comprising a foot member, an arm member, the rear end of the latter overlying a portion of the former, the body portions of said members being disposed in substantially parallel vertically spaced relation, a threaded pin extending upwardly from the upper surface of the underlying portion of the foot member, said pin being received in an opening in the arm member, adjusting nuts threaded on said pin and disposed one below and one above the arm member, and the forward end of said members being spaced apart vertically and laterally.

5. A sewing machine attachment for faggoting work comprising a foot member, an arm member, the rear end of the latter overlying a portion of the former, the body portions of said members being disposed in substantially parallel vertically spaced relation, a threaded pin extending upwardly from the upper surface of the underlying portion of the foot member, said pin being received in an opening in the arm member, adjusting nuts threaded on said pin and disposed one below and one above the arm member, and a needle opening provided in the forward end of the arm member.

6. A sewing machine attachment comprising a cloth-holding foot member and an arm member, said members being spaced apart laterally at their forward ends, and the rear end of the arm member being superimposed over that of the foot member, the body portion of said members being disposed in substantially parallel vertically spaced relation, an upstanding threaded pin carried by the underlying portion of the foot member and passing through an opening in the arm member, adjusting nuts threaded on said pin, one below and one above the rear end of the arm member and contacting the latter to support and adjust it vertically on the pin.

7. A sewing machine attachment comprising a cloth-holding foot member and an arm member, said members being spaced apart laterally at their forward ends, and the rear end of the arm member being superimposed over that of the foot member, the body portion of said members being disposed in substantially parallel vertically spaced relation, an upstanding threaded pin carried by the underlying portion of the foot member and passing through an opening in the arm member, adjusting nuts threaded on said pin, one below and one above the rear end of the arm member and contacting the latter to support and adjust it vertically on the pin, and guide means cooperating with said pin to prevent relative lateral movement of the arm and foot members.
